UNITED STATES PATENT OFFICE.

SAMUEL H. SCHENCK, OF ZIONSVILLE, INDIANA.

IMPROVED MACHINE FOR SPLITTING AND SKIVING LEATHER.

Specification forming part of Letters Patent No. **58,681**, dated October 9, 1866.

To all whom it may concern:

Be it known that I, SAMUEL H. SCHENCK, of Zionsville, in the county of Boone and State of Indiana, have invented a new and Improved Mode of Splitting and Skiving Leather; and I do hereby declare that the following is a clear, full, and exact description thereof, reference being had to the accompanying drawings, and to the letters of reference marked thereon.

The nature of my invention consists in constructing two cheeks, 7 7, of semicircular shape, and placing between them a segmental skiving-block, 1. This block turns on a pivot at 9, and is regulated or set to the knife 2 by means of the set-screw 6. 3 is a lever which works on a pivot at 10, and to it is fastened the knife 2 by means of set-screws 4 4.

For splitting leather, I use the roller 5, between which and the knife 2 the strap has to pass to be split. The roller 5 is set with the same set-screw, 6, which adjusts the block 1.

What I claim, and desire to secure by Letters Patent of the United States, is—

1. The cheeks 7 7, the adjustable skiving-block 1, the knife 2, and its attachment to the lever 3.

2. The roller 5, in connection with the skiving process and the set-screw 6, all arranged and operating substantially as set forth and described.

SAMIL. H. SCHENCK.
